UNITED STATES PATENT OFFICE

1,932,466

SQUEEZING MOP

Goro Kawasaki, Los Angeles, Calif.

Application May 31, 1930. Serial No. 458,112

1. Claim. (Cl. 15—119)

An object of this invention is to provide means whereby the user of a mop may wash and thoroughly clean a mop-cloth without wetting or soiling his hands.

5 An object of the invention is to provide a device of this character which is easily made by machinery and in which the mop-cloth clamping parts are firmly held together by simple and convenient resilient means, and in which a simple and conveniently secured spring is provided to apply pressure upon the mop-cloth to squeeze the water out of it, and to so arrange the spring that it serves as a hand guard to avoid any likelihood of hurting the hand by operation of the

10 15 mop cloth holder and squeezer.

Another object is the provision of cheap and simple anti-friction means for applying the squeezing pressure to the mop-cloth.

The invention also includes a novel means for 20 releasably holding the mop-cloth in the mop head.

The invention includes the various parts, combinations and arrangement of parts hereinafter more particularly described and claimed.

25 Advantages are facility of manufacture by machinery and facility and ease of fastening the mop-cloth in the mop head and of using and cleansing the mop-cloth.

Other objects, advantages and features of invention may appear from the accompanying drawing, the subjoined detailed description and the appended claim.

The accompanying drawing illustrates the invention.

35 Figure 1 is an edge view of the mop ready for use in mopping.

Fig. 2 is a flat side view of the device shown in Fig. 1, with parts in position while squeezing water out of the mop-cloth.

40 Fig. 3 is a fragmental edge view of the mop-cloth holder and squeezer with parts in position shown in Fig. 1, but omitting the mop-cloth.

Fig. 4 is a section on line indicated by x4, Fig. 5, and taken axially of the mop handle and levers 45 and transversely of the mop-cloth holder.

Fig. 5 is a side view of the mop-cloth holder closed without the mop-cloth.

Fig. 6 is a view of the mop-cloth holder with parts shown intermediate the clamping and releasing positions; the mop-cloth being omitted.

Fig. 7 is a view of the five parts of the mop head disassembled without reversal.

Fig. 8 is a top view of the mop-cloth holder looking down from line x8, Fig. 6.

55 Fig. 9 is a view looking into the mop-cloth seat.

Fig. 10 is a section on line x10, Fig. 5.

Fig. 11 is an end elevation of the mop-cloth seat.

Fig. 12 is a section on line indicated at x12, Figs. 6 and 10.

Fig. 13 is a section on line x13, Figs. 6, 9 and 10.

Fig. 14 is a section on line x14, Figs. 6, 9 and 10.

Fig. 15 is a section on line indicated at x15, Figs. 6 and 10.

This device comprises a mop-cloth holder 1, a handle 2 to the end of which the holder is fastened, and a mop cloth squeezer having jaws 3, and slidably mounted relative to the mop cloth holder and handle by a slide 4.

Said squeezer jaws are carried by grip levers 5 pivoted to the slide by rivets 6, and yieldingly held towards each other by a spring belt 7 mounted by rests 7' on the grip levers, and serving as a fender to protect the hand of the operator at the time the squeezer is moved relative to the 75 mop cloth holder.

In general terms it is not new to provide, in combination, a mop cloth holder, a mop cloth squeezer in slidable relation thereto, and provided with grip handles for opening the jaws of the 80 squeezer. The elements which might be defined by such broad terms are found in my Patent No. 1,137,760, patented May 4, 1915 for Mop, and over which mop my present invention is an improvement in various particulars.

Again referring to the drawing herein, the mop cloth holder comprises two plates 8 and 8', which are originally of like stampings each adapted to constitute one-half of a mop cross-head and provided with a segmental handle socket imprint 9 provided with a perforation 10 to accommodate a handle securing rivet 11; and each plate is in the form of a flat web 12 and flaring marginal flange 13 adapted and arranged to form with the flange of a companion plate, an angular trough-like mop-cloth holding groove 14, when the plates are secured together by suitable means as by the eyelet rivets 15 as shown in the drawing.

By preference, the plates are mainly flat and are adapted to fit together when they are placed against each other with the concavities of the imprints 9 facing each other to fit the handle.

The mop head is formed of the two plates suitably fastened together.

105 Each of said plates comprises a broad neck 16 and cross-head arms 16', having the half handle socket imprint 9 and perforation 10; and the cross-head is provided with inner mop cloth gripping teeth or detents 17, and is provided in

opposite faces of the cross-head with transverse stiffening ribs 18 projecting from the outside faces of the cross-head.

The mop-cloth 19 may be of any approved character and is shown as being made up of strands fastened together at their mid-length and adapted to be bent at the middle over a latch bar 20 constructed and arranged to fasten the mop-cloth into the groove 14.

10 The grooves formed by the cross-head flanges on each side of the neck or socket piece 16 form wire-holding seats 21. The plates are provided with holes 22 for the eyelet rivets 15 that hold the plates together.

15 In combination with the mop-head just described, there is provided a mop-cloth holder comprising three spring wire links, one of which is the latch bar 20 and two of which are attaching links 23, 24, that are mainly alike, as indicated in Fig. 7; the latch bar 20 having at one end an eye 25 for pivotal engagement with one attaching link, and having at the other end a hook 26 for detachable engagement with the other attaching link.

20 When the stampings 8, 8' have been riveted together as indicated in Figs. 5, 6, and 10, with their flat faces together and the flaring edges 27, 27' of the cross-head arms forming open grooves to receive and seat the tongues 23, 23' of the attaching links, and when the attaching tongue of link 23' has been seated, the flaring edges at 27' are crimped onto the end of the tongue 23' to fix said tongue to the cross-head arm; and the remainder of the attaching link, including the coil 35 29, straight limb 30, bend 31, intermediate limb 32, bend 33 and eye 34, is free to act as a spring; and the attaching latch bar 20, when fixed in the groove, extends around the end of the cross-head; and the eye 34 is transferred to the mid-plane of the attaching latch bar.

25 When the mop-cloth fastening device is assembled as shown in Fig. 5 the latch bar 20 is placed under a strain by the tension of the tongues 23, 23' and their spring coils 29; and the eye 45 terminated limbs of the links 23 and 24 exert a constant pressure upon said latch bar to hold the mop-cloth 19 in the channel between the flaring edges 27 at the lower edge of the cross-head.

30 The flaring edges at the top of the cross-head limbs are both originally spread apart as indicated at 27 on the left side of Fig. 8 to readily admit the tongue, as 23', of an attaching link, and after the tongue, as at 23', has been inserted into the corresponding seat 27', seen at the right in Figs. 5, 6 and 8, the lips or flanges as at 27', of the seat will be crimped together over the link tongue marked 23' in Figs. 5 and 6, so as to hold said link in fixed position relative to the cross-head.

35 Said links 23, 24, are each provided with an intermediate spring coil 29 and each is thence formed in a limb 30, a right angle bend 31, a limb 32, a bend 33, and terminates in an eye 34; and in practice, the link 23 is hinged by the eye 34 to the intermediate latch bar 20.

40 The eye 34 and the bend of the hook 26 are in a common plane; and when the tongue 23' of the attached link 23 is seated in the seat therefor, and secured by crimping the edges of said seat over said tongue, as at 23', the eyes 34 and 34' of the attaching links 23, 24, extend trans-

versely to the mid-plane of the links and the spring extensions formed of the parts 30, 31, 32 and 33, play in the channel 35 between the uncrimped portions of the flanges at the end of the cross-head, thus allowing the hook 26 to be inserted into the eye 34 of the link 23; and when the eye 34 of the link 23 is connected to the eye of the latch link 24, the tongue 23 can be inserted into the seat therefor at the opposite end of the cross-heads by which the latch bar 20 may be put under tension in the seat formed by the flanges.

45 The latch lever 24 thus acts in connection with the latch bar 20 to operate as a toggle joint to spring the parts together into the position shown in Fig. 5 when the link 24 is rolled over in the seat between the flanges.

50 The squeezer levers 5 are provided with end sockets 5' which are adapted respectively to seat the shanks 36 and 36' of the roller carrying frames 37 and 37' on which the rollers 38 and 38' are mounted; the shanks of one of said frames having at each end of the roller an extended loop 39 projecting across the ends of the mop head and across the opposite roller frame so that when the squeezer is shoved down from the position shown in Fig. 2, thus to compress the mop-cloth 19 between the rollers, and thus to squeeze water out of the cloth, the extended loops 39 serve as guards at the sides of the mop-cloth. The handle 100 ends of the levers 5 are bent outwardly as indicated, so that by squeezing the squeezer handles onto the mop handle, the mop squeezer frames or jaws are separated sufficiently to allow the squeezer to be drawn up past the cross head 105 and to allow the mop-cloth to hang down as indicated in Fig. 1, during the return operation.

55 In practical use the parts may be in the position shown in Figs. 1, 3 and 4, and by swinging the latch wire 20 down as will be readily understood, the mop-cloth can be brought into position on the latch wire 20 and then fastened as above described, and the scrubbing or mopping of the floor can be affected in the usual way, the cloth being wetted in a pail of water; and when it is 110 desired to squeeze the cloth into another vessel, or elsewhere, the operator will shove down on the slide 4, thus shoving the squeezing rollers down to express the water from the mop cloth; then the squeezing rollers may be retracted by 115 reverse movement of the slide 4 and the mop-cloth may be rinsed or dipped into the water in the pail; and if desired the excess water may be 120 squeezed out by operating the squeezer as above described, and the work may be proceeded with 125 in the manner readily understood from the foregoing.

60 I claim:—

65 In a mop provided with a handle and a cross head and means to secure a mop-cloth to the cross head; squeezing frames of wire provided with rollers; one of said frames having opposite sides bent into loops extending across the other frame and the intermediate space, to form a guide-way for the mop cloth; handles secured to said frames; a slide movable longitudinally of the mop handle to which the handles are pivoted and spring means for pressing the squeezer frames toward each other.

70 GORO KAWASAKI. 145
